DESIGN FOR A PLAY TABLE

Harry Zimmerman, New York, N. Y.

Application February 23, 1940, Serial No. 90,449

Term of patent 7 years

To all whom it may concern:

Be it known that I, Harry Zimmerman, a citizen of the United States, residing at New York, in the county of New York and State of New York, have invented a new, original, and ornamental Design for a Play Table, of which the following is a specification, reference being had to the accompanying drawing, forming part thereof.

In the drawing

Fig. 1 is a perspective view of a Play Table with the compartment cover partly open, showing my new design;

Fig. 2 is a side elevational view and Fig. 3 is a rear elevational view thereof.

I claim:

The ornamental design for a play table, as shown.

HARRY ZIMMERMAN.
